UNITED STATES PATENT OFFICE.

WILLIAM A. DANIEL, OF EARL, ARKANSAS.

PASTE-DISPENSING DEVICE.

1,384,307.

Specification of Letters Patent. Patented July 12, 1921.

Application filed July 23, 1920. Serial No. 398,422.

To all whom it may concern:

Be it known that I, WILLIAM A. DANIEL, a citizen of the United States, residing at Earl, in the county of Crittenden and State 5 of Arkansas, have invented a new and useful Paste-Dispensing Device, of which the following is a specification.

It is the object of this invention to provide novel means for holding and folding 10 a flexible tube, to the end that the contents of the tube may be dispensed.

With the above and other objects in view, which will appear as the description proceeds, the invention resides in the combination 15 and arrangement of parts and in the details of construction hereinafter described and claimed, it being understood that, within the scope of what is claimed, changes in the precise embodiment of the invention 20 shown can be made without departing from the spirit of the invention.

In the accompanying drawings:—

Figure 1 shows in side elevation, a device constructed in accordance with the invention; Fig. 2 is an end elevation; and Fig. 3 is a plan view.

In carrying out the invention there is provided a holder made of wire or any other resilient material. The holder comprises forward arms 1 which are convexed as indicated at 2, the arms 1 merging into a loop-shaped head 3 disposed approximately parallel to the arms, the arms and the head being connected by diverging laterally extended loop-shaped guides 4. The forward arms 1 are continued to form rear arms 5 which are convexed as shown at 6, like the forward arms 1. The rear arms 5 are disposed, if desired, at a slight angle to the 40 arms 1. Those portions 7 which connect the arms 1 and 5 may pass through, or be otherwise assembled with, a base 8 having openings 9 adapted to receive securing elements (not shown) whereby the base may 45 be secured to a support 10. The support 10 may be a shelf or it may be a vertical wall, depending upon the taste of the user, the device being so constructed, ordinarily, that it will discharge downwardly.

50 The drawing shows an ordinary flexible tube in which tooth paste, shaving cream and the like are contained, the tube including a body 11, a head 12 and a nozzle 14. In practical operation, the tube is thrust between the arms 1—1 and 5—5, the arms

1—1 engaging the body 11 of the tube immediately in the rear of the head 12, the arms 5 engaging the body 11 of the tube at some distance from the head. The body 11 of the tube is received in the convexed portions 2 of the arms 1 and in the convexed portions 6 of the arms 5. The loop-shaped member 3 serves as an abutment for the head 12 of the tube and prevents the tube from sliding longitudinally. If the tube 65 should be pushed far enough in the arms 1—1 and 5—5, in the direction of the length of the arms, then the nozzle 14 of the tube may engage with the curved portion of the head 3.

70 A means, independent of the holder, is provided, for folding the rear end of the tube. This means may be of any desired sort. A clamp, which may be a cotter pin 15 may be used, a finger piece 16 being 75 thrust through the eye of the cotter pin. The rear end of the tube is flattened, and is inserted between the arms of the cotter pin 15, and when the cotter pin is rotated, the body 11 of the tube will be folded, the contents of the tube being expelled.

Having thus described the invention, what is claimed is:—

1. In a device for dispensing paste from 85 flexible tubes, a holder comprising tube-gripping forward arms merging into a loop-shaped head forming an abutment for the forward end of the tube, the forward arms being prolonged to form rear tube-gripping arms; and a base, the holder being connected to the base between the forward and rear arms.

90 2. In a device for dispensing paste from flexible tubes, a holder comprising tube-gripping forward arms merging into a 95 loop-shaped head forming an abutment for the forward end of the tube, the forward arms and the head being connected by diverging loop-shaped guides, the forward arms being prolonged to form rear tube-gripping arms; and a base, the base being connected to the holder between the forward and rear arms.

100 In testimony that I claim the foregoing as my own, I have hereto affixed my signature in the presence of two witnesses.

WILLIAM A. DANIEL.
